UNITED STATES PATENT OFFICE.

CHARLES C. GRUHLER, OF FORT THOMAS, KENTUCKY.

LOOSE-LEAF BINDER.

Application filed March 7, 1927. Serial No. 173,456.

The present disclosure of the invention relates to loose leaf binders of a type embodying a channel-shaped back member having hinge means permitting outward swinging of its opposite sides, for the purpose of moving leaf-impaling fingers carried by said sides, out of overlapping relation with each other, allowing removing, transposing, insertion or adjustment of leaves, as occasion 10 may demand.

It is one object of the invention to provide unique means, in a device of this character, for normally holding the opposite halves of the channel-shaped back member against outward swinging, said means however, being releasable to permit such swinging when desired.

The invention further relates to a loose leaf binder in which, at least one set of the 20 leaf-impaling fingers is carried by a slide strip, means being provided for normally holding the strip against sliding, so that the fingers of the one set, extend into overlapping staggered relation with the fingers 25 of the other set. It is a further object of the invention to construct the slide strip, the mounting means therefor, and the holding means for said strip, in such a manner that upon release of said holding means, the strip 30 may be bodily slid from the remainder of the binder, or may be slid sufficiently to bring fingers of the one set into alinement with fingers of the other set, permitting transfer of sheets from one half of the binder 35 to the other.

Preferably, both sets of the fingers are carried by slide strips, and it will be seen that by having these strips and the two sets of fingers carried thereby, removable entirely 40 from the remainder of the binder, the leaves from either or both halves of said binder, may be bodily removed whenever this should become desirable. Normally, the leaves of either half of the binder are segregated from 45 those of the other half, due to the normal staggered relation of the fingers of the two sets, said relation preventing sliding of leaves from one-half of the book to the other, until the two sets of fingers are relatively set to permit such sliding.

With the foregoing in view, the invention resides in the novel subject matter herein-after described and claimed, the description being supplemented by the accompanying 55 drawings.

Fig. 1 is a perspective view of a loose leaf

binder constructed in accordance with my invention.

Fig. 2 is a sectional view as indicated by line 2—2 of Fig. 1.

Fig. 3 is a sectional view at right angles to Fig. 2, as indicated by line 3—3 of Figs. 1 and 2.

Fig. 4 is a view similar to Fig. 3, but illustrating the opposite sides of the channel-shaped back member swung outwardly from each other.

Fig. 5 is a detail view similar to a portion of Fig. 2, the means for normally holding the opposite sides of the back member against outward swinging, being shown in released position.

Fig. 6 is a detail sectional view on line 6—6 of Fig. 2, illustrating primarily, the preferred form of locking means for the finger-carrying, slide strips.

In the drawings above briefly described, certain specific details have been shown for illustrative purposes, and while these details will be rather specifically described, it is to be understood that within the scope of the invention as claimed, variations may be made.

The numeral 7 designates a channel-shaped back member to which the front and back 8—9 of the binder, are hingedly connected by any desired means 10, said back member 7 preferably consisting of two right-angular sections hinged together at 11, so that the opposed sides 12 of said member, 80 may swing outwardly (see Fig. 4) when desired. Novel provision is made however for normally holding the sides 12 in fixed relation with each other, as seen in Figs. 1 and 3.

Near each end of the back member 7, I provide two slidably connected stays 13—14, said stays being pivoted at 13^a and 14^a, respectively, to the sides 12 of the back member 7, the pivotal axes being parallel with 100 the hings 11. It will thus be seen, that as long as the stays 13—14 are held against relative sliding, the back member 7 must maintain a rigid, channeled form as seen in Figs. 1 and 3. When relative sliding of the 105 stays is permitted however, the sides 12 of the back member 7, may swing outwardly as shown in Fig. 4, and again inwardly to their normal positions.

Preferably, the stays 13—14 are in the 110 form of flat strips which slidably overlap each other, the strip 13 being provided at

its free end with fingers 13^b which slidably embrace the strip 14, while the latter strip is equipped with fingers 14^b which slidably engage the strip 13.

The two strips 14 carry aligned guides 15 which slidably receive a rod 16, and this rod carries a pair of wedges 17 disposed at the outer sides of the strips 13, said wedges preferably having hubs 18 secured by set 10 screws 19 upon the rods. By this construction, when the rod 16 is slid in one direction, the wedges 17 and rod 16 will effect tight clamping of the strips 13 and 14 together, so that the sides 12 of the back member 7 cannot swing outwardly. However, when rod 16 is slid in the opposite direction, as seen in Fig. 5, the wedges 17 free the strips 13—14, for relative sliding, permitting the back member 7 to open about the 20 hinge 11 as seen in Fig. 4. For sliding the rod 16 in the necessary manner, I prefer to provide it with a laterally turned end 20, and to limit the movement of said rod which releases the wedges 17, stop collars 21 may 25 well be secured on said rod to strike the guides 15.

In the preferred form of construction, each wedge 17 is provided with a plurality of longitudinally disposed ridges 17^a, and 30 the co-acting strip 13, is formed with transverse ridges 17^b, the two sets of ridges inter-engaging each other as clearly shown in Figs. 2 and 3 to positively hold the strips 13—14 against relative sliding. This locking of the strips may be effected either when 35 the back member 7 is closed as in Fig. 3 or open as in Fig. 4.

Channel-shaped guideways 22 have been shown secured to the inner faces of the sides 40 12, and two slide strips 23 are engaged with these guideways, each of said strips carrying a set of leaf-impaling fingers 24. The fingers of one set normally extend into overlapping relation with the fingers of the 45 other set as seen in Figs. 1 and 3, and the fingers of the two sets are then disposed in staggered relation. Hence, no leaves impaled upon one set of fingers can slide onto the other set, under normal circumstances. 50 However, when the back member 7 is opened as shown in Fig. 4, the slide strips 23 may be relatively adjusted, so that fingers of one set may be brought into alignment with those of the opposed set. Hence, the leaves may readily be transferred from one 55 half of the binder to the other. Moreover, attention is invited to the fact that the slide strips 23, the guideways 22, and locking means for said slide strips (yet to be described) are all of such construction that 60 upon release of said locking means, either or both of the strips 23 may be slid entirely from the back 7, and thus the leaves from either or both halves of the binder may be 65 bodily removed whenever this is desired.

Sliding of the strips 23 is also advantageous for certain other purposes which need not be herein stated.

The locking means above referred to, for the slide strip 23, preferably comprises an 70 arm 25 pivoted at 26 to one end portion of the guideway 22, said arm having a lateral end 27 for reception in a notch 28 in the strip 23. This construction is shown clearly in Figs. 2, 5 and 6. When the arm 25 is 75 in the position of Figs. 2 and 6, the slide strip 23 is held against sliding but when said arm is swung to the position of Fig. 5, sliding of said strip to any desired extent, in either direction, is allowed.

From the foregoing, taken in connection with the accompanying drawings, it will be seen that I have provided a generally improved loose leaf binder whose principal novelty resides in the manner of slidably 85 mounting the fingers 24 and in the provision which has been made for normally holding the sides 12 of the back member 7, in rigid relation with each other. While again referring to this means, attention may 90 be invited to the fact that the free end of strip 14 preferably abuts hinge 13^a, and the free end of strip 13 preferably abuts hinge 14^a, when the back 7 assumes its normal position. Hence, the inward movement of the 95 sides 12 toward each other, is limited and the hingedly connected portions of the back 7, cannot move outwardly beyond the intended position.

I claim:

1. In a loose leaf binder having a channel-shaped back member provided with hinge means permitting outward swinging of its opposed sides; two slidably connected stay members jointly extending between said sides and pivoted thereto respectively on axes parallel with the hinge axis, and releasable means embodying a wedge for normally holding said stay members against relative sliding to hold said sides in fixed relation 100 with each other.

2. In a loose leaf binder having a channel-shaped back member provided with hinge means permitting outward swinging of its opposed sides; two slidably connected stay members jointly extending between said sides and pivoted thereto respectively on axes parallel with the hinge axis, and releasable means for normally holding said stay members against relative sliding to hold said sides in fixed relation with each other, said releasable means embodying a wedge for holding said stay members tightly together.

3. In a loose leaf binder having a channel-shaped back member provided with hinge means permitting outward swinging of its opposed sides; two slidably overlapped stay strips jointly extending between said sides and pivoted thereto respectively on axes par-

allel to the hinge, a guide extending transversely of the outer side of one of said strips, a wedge to engage the outer side of the other of said strips, and a rod carrying 5 said wedge, said rod slidably engaging said guide to mount the wedge for sliding transversely of the stay strips, said wedge and rod when in one position holding said strips tightly together to resist relative sliding of 10 said strips.

4. A structure as specified in claim 3; together with longitudinal ridges on the wedge, and transverse ridges on said other strip, the two sets of ridges engaging each 15 other when the wedge is in said one position and thereby positively holding the two strips against relative sliding.

5. In a loose leaf binder having hingedly connected members, a set of leaf-impaling fingers carried by one of said members, a slide strip carrying a second set of fingers, means slidably mounting said slide strip on the other of said members, the fingers of said one set normally extending into overlapping relation with the fingers of said second set, and means for normally holding said slide strip against sliding; said slide strip being freely slideable entirely from said mounting means upon release of said holding means, permitting leaves from one half 30 of the binder to be bodily removed; sliding of said strip also permitting alinement of fingers of the two sets to permit transfer of

sheets from one half of the binder to the other.

6. In a loose leaf binder having a channel-shaped back member provided with hinge means permitting outward swinging of its opposed sides, and releasable means normally preventing such outward swinging; 40 two opposed guideways carried by said sides of said back member and extending longitudinally thereof, two slide strips engaged with said guideways and extending substantially throughout the length of the back 45 member, two sets of leaf-impaling fingers secured to said strips respectively, the fingers of one set normally extending into overlapping relation with and being staggered with respect to those of the other set, and releasable means for holding said slide strips normally against sliding; either strip being freely slideable entirely from its respective guideway when the first and last named holding means are released and the sides of 55 the channel-shaped back are spread apart, thereby permitting the leaves from either half of the binder to be bodily removed; sliding of the strips also permitting alinement of fingers of the two sets to permit 60 transfer of sheets from one half of the binder to the other.

In testimony whereof I have hereunto affixed my signature.

CHARLES C. GRUHLER.
